UNITED STATES PATENT OFFICE.

EDWARD HOLMES AND BRITAIN HOLMES, OF BUFFALO, NEW YORK.

MACHINE FOR PLANING BARREL-HEADS.

SPECIFICATION forming part of Letters Patent No. 292,816, dated February 5, 1884.

Application filed February 11, 1881. (No model.)

To all whom it may concern:

Be it known that we, EDWARD HOLMES and BRITAIN HOLMES, both citizens of the United States, residing in Buffalo, in the county of Erie and State of New York, have invented 5 certain new and useful Improvements in Machines for Planing Barrel-Heads, of which the following is a specification.

The object of this invention is to provide the 10 means for planing barrel-heads or other lumber of different thicknesses; and it consists in certain combinations of the boxes, gearing, and other connections, whereby the gear-wheels are always kept in place and work freely without cramping or being moved out of gear, and the pressure-rollers are adapted to rise and fall at either end or side of the machine without being in any way affected by the power required to operate them, all of which will be 15 20 more clearly hereinafter shown by reference to the drawings, in which—

Figure 1 is a plan or top view of the machine; Fig. 2, an enlarged detached view of the back box for holding the back gearing and driving-pulleys and the back end of one of the 25 feeding-roller shafts. Fig. 3 is an enlarged longitudinal section through the center of the two front boxes which hold the front ends of both the feeding-roller shafts. Fig. 4 is a perspective 30 view of one of said front boxes. Fig. 5 is a side elevation of Fig. 2; Fig. 6, a front view of a portion of Fig. 2. Fig. 7 is a horizontal section through the same, showing a top view of the oscillating box. Fig. 8 is a front elevation 35 of the machine, and Fig. 9 represents a side elevation.

The frame A is held together by the usual binding-rod, A'. (Shown in Fig. 9.)

B represents the bed, upon which the stuff to 40 be planed is placed. The back plate, B', is made adjustable vertically by means of the usual set-screws or bolts, so as to regulate the depth of the cut.

C represents the grooved feed-rollers fastened to the shafts C' C², which shafts work in boxes D, D', D², and D³. The boxes are held down with sufficient force by the weighted levers E E' E² E³, which are jointed by pins or bolts g' to the arms g, the weights F being arranged so they can be moved along said levers, so that the pressure of the feed-rollers C may be adjusted. Each lever E E' E² is provided

with a rod, F', for holding the feed-roller boxes down, said rods being jointed or connected in the usual way to said levers, so as to be adjustable lengthwise. They are arranged so as to pass up above the top of the machine, and terminate in a curved portion, f, adapted to rest upon the top of the boxes and press them down. (See Figs. 1, 8, and 9.) The lever E³, 55 60 the end of which is shown in Fig. 8, is jointed to arms g, projecting from the frame of the machine by a pin or bolt, g', and is otherwise constructed like the levers E, E', or E². It is also jointed in the usual way by a pin or bolt 65 to the lower end at e' of the vertical bar G, (see Fig. 5,) which bar G is connected to or forms a part of the box D², and is adapted to move up or down with it. The bar G is kept 70 in place and in line at the top by the box D², 75 which is provided with a tongue or rib, a, at each end and fitted into corresponding grooves in the frame, so as to be held securely in line and be capable of a free movement up or down. (See Figs. 1, 2, 5, 6, and 7.) The lower 75 end is kept in place by a cap, e, bolted to the frame, so that the bar G shall have a vertical movement up or down. (See Figs. 2 and 5.)

The object in holding the box D² and its vertical bar or brace G securely in line while 80 it has a free up-and-down movement is that it allows all the necessary movements to the box, and carries one end of the feed-roller shaft C', and also the feed-rollers, driving-pulleys, and gearing, or all the gearing necessary for giving the required movements to the feed-rollers at the back end of the machine. 85

To allow the feed-roller shaft C' to oscillate at the back end of the machine as the box D² moves up or down, it is fitted into the rocking box d, arranged in the box D². (See Figs. 6 and 7.) The said box d is provided with flat sides h h, which prevent it from turning in the opening d' in the box D². (Shown in section, Fig. 7, and by the dotted lines in Fig. 6.) 95 The other parts of its surface being rounded, as shown, it is free to rock or oscillate in the direction across the box D². The hole h' is the bearing for the back end of the shaft C', which passes through it and receives the pinion I. (Shown in Figs. 1, 2, and 9.) The box D² is also provided with pins or shafts I' I², (shown in Fig. 7,) rigidly fastened in the holes i i'. (Shown in Fig. 6.) The shaft I'

holds or carries the large gear-wheel J and pinion J', and the shaft I' carries the driving-pulley K, loose pulley K', and the pinion L. By this construction the gearing all moves freely without any danger of binding. The face of the gear-wheel I being made narrow, allows the necessary oscillation of the shaft C' without causing its teeth to bind in the teeth of the pinion J'. The pulley K is shown in Figs. 1, 8, and 9, and the pulley K' and gear-wheel J are shown in Figs. 1 and 9, and are also indicated by the dotted lines J and K' in Fig. 2. The front boxes, D D', which carry the feed-roller shafts C' C', are provided with trunnions b b', which fit in vertical grooves in the openings in the upper part of the frame. (See Figs. 1 and 3.) By this arrangement the boxes can move up or down, or oscillate at either side, or either box can oscillate independent of the other. The two boxes are kept together by a pin or trunnion, c, on the box D, which fits into a corresponding recess in the box D', (see Fig. 3,) so that either may turn on the trunnion without turning the other, or both may turn together. (See Figs. 3 and 4.) The feeding-roller shafts C' C' are geared together by the pinions c' c' and the intermediate connecting-pinion, c'', (see Figs. 1, 8, and 9,) so that a rotating movement given to the shaft C' will be transmitted to the shaft C'', causing it to turn in the same direction, and without in any way causing the gearing to bind, so that they will at all times move easily without being interfered with by the vertical or other movements of the boxes D D'; and the construction is such that the pressure of the feed-rollers will not be affected in any way by the power required to drive them and their connecting-gear, thereby leaving the pressing action of the feed-rollers free to be acted on only by the weights, so that the feeding power is at all times the same.

M represents the driving-pulley for the cutters or planing-knives, which being made in the usual way and well known, will require no further description here.

The operation of the machine is as follows: The usual high speed is given to the cutters by a belt on the pulley M, operated in any well-known way, and the feed-rollers C receive their rotary feeding movement by a belt on the pulley K, which transmits its motion from its pinion L to the large gear-wheel J, and from that by its pinion J' to the gear-wheel I

on the shaft C', thereby operating it and its feed-rollers. The shaft C' and its feed-rollers receive the required movement from the shaft C', and the pinion c', fastened to its opposite end, which transmits its motion to the intermediate pinion, c'', and from that to the pinion c''' on the shaft C'', thereby giving to said shaft and its feeding-rollers the proper feeding movement. The stuff to be planed is passed in over the table B, under the feed-rollers C, in the direction of the arrow. The back end of the shaft C'' is set in a bearing or box, D'', which is also provided with trunnions similar to the boxes D or D', or it may have a rocking box, d, similar to that in the box D', so as to allow the necessary oscillating movement to the box as it rises and falls.

An equivalent device for the trunnions b or b' would be a tongue or rib, a, similar to that shown in Figs. 6 and 7, but having its sides rounded or convex, so that its upper and lower ends would be sufficiently narrow to allow the necessary oscillating or rocking movement to the boxes.

We claim as our invention—

1. The weighted box D', rigidly fastened to or forming a part of a vertical bar, G, and arranged to slide in grooves in the frame of the machine, the bar G being secured in a box near the bottom, and provided with the gearing I J J' L K K', for operating the feeding mechanism, in combination with the shaft C, its feeding-rollers, rocking box d, and the weighted box D, for supporting the opposite end of the shaft C', and its connecting-gear for operating the shaft C' and its feeding-rollers.

2. The feeding-roller shaft C', its operating mechanism, and weighted movable box D', in combination with the connected movable boxes D D', having an independent oscillating movement one way and a connected movement the other way, substantially as specified, and the pinions c', c'', and c''', for giving the necessary feeding movement to the shafts C' C'' and their feeding-rollers without interfering with the upward or downward movements of the said pressure and feeding rollers by reason of the action of the gear-wheels upon each other, substantially as described.
